UNITED STATES PATENT OFFICE.

JOHN HERZOG, OF SAGINAW, MICHIGAN, ASSIGNOR TO THE REGINA COMPANY, OF RAHWAY, NEW JERSEY, A CORPORATION OF NEW JERSEY.

DESIGN FOR A CABINET.

No. 39,970.

Specification for Design.

Patented May 4, 1909.

Application filed February 19, 1909. Serial No. 479,012. Term of patent 7 years.

To all whom it may concern:

Be it known that I, JOHN HERZOG, a citizen of the United States, and resident of Saginaw, county of Saginaw, and State of Michigan, have invented a certain new, original, and ornamental Design for Cabinets, of which the following is a specification.

Reference is to be had to the accompanying drawings in which—embodying my new design; and Fig. 2 is a plan view of said cabinet.

I claim—

The new, original and ornamental design for a cabinet as shown.

JOHN HERZOG.
